PILLOW

Hugh Cecil Sheasby, Kimberley, South Africa

Application March 4, 1936, Serial No. 67,116

4 Claims. (Cl. 5—71)

This invention relates to pillows and has for the primary object the provision of a device of this character which is especially adapted for beds to provide a comfortable and adjustable headrest for a person while lying on the stomach 5 with the face down and which will permit the person to breathe freely by having the nose and mouth unobstructed while the remaining portions of the face are comfortably supported.

With these and other objects in view, this invention consists in certain novel features of construction, combination and arrangement of parts to be hereinafter more fully described and claimed.

For a complete understanding of my invention, reference is to be had to the following description and accompanying drawing, in which

Figure 1 is a vertical sectional view illustrating a pillow constructed in accordance with my invention.

Figure 2 is a plan view illustrating the pillow frame.

Figure 3 is a plan view showing the pillow.

Figure 4 is a fragmentary sectional view showing the means of attaching the pillow to the pillow frame.

Referring in detail to the drawing, the numeral 1 indicates a substantially rectangular-shaped frame and has hinged to one end thereof an adjustable frame 2, the latter also being connected 30 to the frame 1 by adjustable braces or standards 3 each composed of telescopic sections 4, which sections are held in adjusted position by set bolts 5. The standards 3 provide means whereby the frame 2 may be adjusted to various inclinations 35 with respect to the frame 1.

A ring-like member 6 is yieldably supported to the frame 2 by a plurality of radially arranged cushion elements 7. The elements 7 may be in the form of coil springs or any other equivalent 40 device. A pillow 8 consisting of a covering 9 and padding 10 is supported by the elements 7 and the covering 9 is secured to the ring-like member 6 by lacings 11. The pillow is formed to provide therein an opening 12 positioned in 45 alignment with the space defined within the ring-like member 6. The opening 12 is shaped to permit a person's mouth and nose to be fully exposed or uncovered when the face is resting upon the pillow so that a person's breathing when 50 face down upon the pillow may be free and unobstructed. The pillow being supported by the frame 2 at a desired inclination and spaced from

the frame 1 when resting upon a bed will permit free circulation of air to the person's mouth and nose.

Having described the invention, I claim:

1. A pillow comprising a supporting frame, a second frame adjustably connected to the first frame, a plurality of radially arranged resilient elements connected to the second frame, a ring-like member supported by the resilient elements, a pillow having a nose and mouth opening supported by the resilient elements with the opening aligning with the ring-like member, and means for securing the pillow to the ring-like member. 5

2. A pillow comprising a supporting frame, a second frame, means for adjustably supporting the second frame in spaced relation to the first frame, a plurality of radially arranged resilient elements having their outer ends connected to the second frame, a ring-like member connected to the inner ends of the resilient elements, a pillow having a nose and mouth opening supported 10 by the resilient elements with the opening aligning with the ring-like member, and means for securing the pillow to the ring-like member with the opening in the pillow in registry with the ring-like member. 15

3. A pillow comprising a supporting frame, a second frame adjustably connected to the first frame, a plurality of radially arranged resilient elements connected to the second frame, a ring-like member supported by the resilient elements, 20 a pillow having a nose and mouth opening supported by the resilient elements with the opening aligning with the ring-like member, and means for securing the pillow to the ring-like member with the opening in the pillow in registry with the ring-like member. 25

3. A pillow comprising a supporting frame, a second frame adjustably connected to the first frame, a plurality of radially arranged resilient elements connected to the second frame, a ring-like member supported by the resilient elements, 30 a pillow having a nose and mouth opening supported by the resilient elements with the opening aligning with the ring-like member, and lacing securing the pillow to the ring-like member. 35

4. A pillow comprising a supporting frame 35 adapted to be supported by a bed mattress, a second frame pivotally connected to the supporting frame, means for adjustably supporting the second frame in spaced relation to the first frame whereby an air space is provided between 40 the two frames permitting the free circulation of air therethrough, a plurality of radially arranged resilient elements one end of each being connected to the second frame, a ring-like member having the other ends of the resilient elements 45 connected thereto, a pillow supported by the resilient elements and having a nose and mouth opening aligning with the ring-like member and opening into said air space, and lacing securing 50 the pillow to the ring-like member. 50
